STRAP FOR WRIST WATCHES

Filed Feb. 8, 1932

UNITED STATES PATENT OFFICE

2,086,050

STRAP FOR WRIST WATCHES

Abraham Schwalberg, Brooklyn, N. Y.

Application February 8, 1932, Serial No. 591,610

16 Claims. (Cl. 24—265)

This invention relates to wrist watch straps or bracelets, and contemplates the provision of a wrist watch strap designed to be quickly and easily connected to various wrist watches, regardless of differences in the shapes and sizes of the strap receiving elements of such watches.

The various objects of my invention will be clear from the description which follows and from the drawing, in which,

13 Fig. 1 is a front elevation of part of my new strap, as it appears in use.

Figs. 2 to 9 are fragmentary elevational views of modified forms and arrangements of my new strap showing a number of the various positions 15 in which it may be secured to a watch provided with a spring-pin strap holding element.

Fig. 10 is a similar view of a modified form of my invention as it appears applied to a wrist watch provided with a central ear or lug.

20 Fig. 11 is a similar view of the same, showing the application of my invention to a wrist watch provided with a pair of spaced lugs or ears.

Fig. 12 is an enlarged fragmentary rear elevational view of the same, similar to Fig. 9, but 25 showing the strap secured to a fixed watch pin.

Fig. 13 is a top plan view and partial horizontal section of Fig. 12.

Fig. 14 is a similar view of Fig. 6, and

30 Fig. 15 is a similar view of the strap end, connection and watch pin of Figs. 1 to 5 inclusive.

It will be understood that wrist watches as at present marketed are provided with variety of different forms of ears or lugs to which it is intended that wrist watch straps or bracelets of 35 predetermined width be attached. Four forms of such ears are illustrated, for example, in Figs. 1, 10, 11, and 12. It has heretofore been necessary, therefore, to supply the jeweler or other retailer of such straps with straps of various widths 40 and shapes, so that he might select a strap to fit the particular watch.

I have made it possible, however, for the jeweler to keep in stock, a strap of standard size made in accordance with my invention, so that 45 the same strap may be attached to the ear or ears of any watch regardless of the position of the ear or ears or the width or spacing thereof.

In Figs. 1 to 9 inclusive, I have shown the watch 18 provided with the same kind of parallel 50 spaced ears or lugs 11 and 12 of comparatively little thickness, and of a type quite frequently used. Said ears are perforated respectively as at 13 and 14 for the reception of a pair of thin plunger pins 15, each arranged partly inside of 55 the main pin 16, and spring-pressed outwardly in

a manner which is well known and hence which need not be further described. The main pin 16 is of greater diameter than the perforations 13 and 14, and is removable from the ears by first pressing at least one of the plunger pins 15 inwardly against the action of its spring to clear the watch ear.

In that form of the watch ear shown in Fig. 10, a single perforated ear as 17 is provided, adapted to receive a suitable pin preferably in the form of a bolt or screw. In Fig. 11, I have illustrated a watch provided with a pair of comparatively wide ears as 18 and 19, said ears being comparatively closely spaced, and being spaced from the edges of the watch 20. In Figs. 12 and 13, the ear is made in the form of a U-shaped pin 21 projecting from and fixed to the watch 22. My invention, however, is applicable not only to all of the various types of watches having the ears just described, but as well as to others known in the art, such as watches having more than two ears, and other types of either fixed or removable pins.

In carrying out my invention, I may make the entire strap body or merely the end portion thereof of a pair of independent sections as 25 and 26, each independently attachable to the watch ear and independently adjustable. The strap end sections 25 and 26 may therefore take various operative positions with relation to each other, and may thereby modify the shape of the strap body, as will be clear from the various figures of the drawing. Or if desired, an integral end section may be provided on the strap, and said section arranged on and secured to a suitable pin in the proper position with the aid of tubular spacers, as will be later explained, in which case the strap is made of minimum width to fit the least space between any pair of watch ears.

In that practical embodiment of my invention which I have illustrated by way of example in Fig. 1, the strap body members 25 and 26 are spread and attached at the left ends 27 and 28 thereof to a suitable buckle or hook of any of the types well known in the art and designated generally by the numeral 29. The buckle, hook or other type of intermediate connection 29 may be permanently attached to the ends 27 and 28 or detachably and adjustably secured thereto. It may take the form of a hinged folding buckle, a solidly attached end hook, an adjustable fastening buckle, or any of the connections at present used for detachably securing strap body sections together and well known in the art, and which hence need no further description. The strap end

which is connected to one side of the watch, being similar to the other end connected to the other side of the watch, the description of one end suffices for both.

5 It will be understood, however, that the ends 27 and 28 of the strap bands may be independently set into and secured to the connection 29, and that the width of said connection should be somewhat greater than the least width of the entire 10 strap body. The strap members 25 and 26 may, if desired, be drawn together at any point into edge to edge contact by one or more suitable loops 30, preferably of leather or metal. At the 15 respective right ends 31 and 32 of the strap members, said members are connected to the watch pin 16 by suitable end hooks as 33. As shown in Figs. 1 and 4, said end hooks each consists of a cylindrical hook or tubular portion 34 at one end passed about the pin 16, the end hook being provided 20 at its other end in a suitably shaped integral portion 35 clamped on to the extreme end of the strap.

In this form of my invention, a pair of independent end hooks 33 are provided, each being 25 separately attached to one of the strap ends 31 or 32. Where the portion 34 is in the form of a hook (Fig. 14) to secure the strap end to the pin, the portion 34 is hooked about and then bent into close contact therewith. Where the portion 30 34 is tubular, the pin 16 need merely be passed therethrough. In either case, however, the portion 34 is made integral with its attaching means 35, but separate from an adjacent portion 34. It being understood that the width of the strap, 35 when the adjacent edges of the body members 25 and 26 are closest together, (Fig. 4) is less than the length of the pin 16, for the narrowest watch with which the strap is to be used, it is desirable to provide means for maintaining the strap ends 40 31 and 32 in their proper positions on the pin.

Toward this end, one or more metallic tubes or spacers 36 of the proper diameter and length are arranged on the pin in any of a variety of positions, depending on how it is desired to space 45 the strap body ends in transversely adjusted position. Connections or hooks as 33 may also be used, if desired, with or without the spacers 36, to attach the ends 27 and 28 of the strap body to the buckle or connection 29.

50 It will be understood that where a single strap section 25 or 26 is used without the other section, the connection or end hook 33 is similarly connected to and adjusted on the pin 16, using the required number of the spacers 36. As shown in Fig. 1, the strap ends 31 and 32 are spread apart and maintained in their spread relation. In that form of my invention illustrated in Figs. 1 and 4, the portions 34 of the end hooks 33 are each made of just sufficient width to receive one of the strap 55 ends, though it will be understood that said portions 34 may be made considerably longer if desired to take the place of separate spacers 36, as will be later pointed out.

Should it be desired to arrange the strap ends 60 31 and 32 comparatively closely together, as shown in Fig. 2, the spacer 36 may be replaced by a shorter intermediate spacer 37, and additional end spacers as 38 and 39, if needed, may be arranged on the pin 16 between the outer edge of 65 each of the end hooks 34 and the adjacent watch ear.

It will be understood that if desired, a series of 70 comparatively short spacers as 42, 43, 44, and 45 may be provided with each strap, so that the user or the jeweler may use as many of said

spacers as is necessary to arrange the strap ends 31 and 32 in any desired relative position on the watch pin 16, as for example illustrated in Figs. 2, 3, and 4. In Fig. 4, the intermediate spacer or spacers have been omitted, and only outer 5 spacers 40 and 41 used. This arrangement may be employed advantageously where the distance between the watch ears 11 and 12 is a minimum.

As shown by the dotted lines in Fig. 5, the cylindrical portions 34 of each of the end hooks may 10 be made integral with each other and elongated as at 46 to such length as to permit the outer edges of the connections 33 to fit between watch ears which are spaced apart to the maximum extent. To assemble the strap members independently on a narrower watch, despite the rigid attachment of the connections to each other, a measured part of the elongated tubular portion 46 is removed by means of a pair of spaced parallel cuts. When the remaining non-separated 15 parts of the section 46 are assembled, the cut ends 47 thereof are in contact and the strap members become arranged in the desired position on the watch pin (Fig. 5). It will be understood that instead of extending the cylindrical portions 46 20 toward each other, they may extend away from each other, and may similarly be cut off at their outer ends to fit inside of the watch ears, so that when assembled, the strap parts assume the positions shown in Fig. 4. In this case, however, the 25 spacers 40 and 41, instead of being separate members, are formed integrally with the remaining tubular pin-receiving portions 34 of the end hooks 30 33.

As illustrated in Fig. 7, it will be seen that my 35 invention is equally applicable to round or cylindrical strap members 48, 49, as to the flat strap members 25 and 26. For round members, however, the terminal portion 50 of the end hook 51 is suitably shaped to be properly clamped about 40 a round strap.

As shown in Fig. 8, the transversely separable ends 52 and 53 of the strap body may be formed by slitting a leather strap body of the usual construction by means of a suitable slit 54; or the 45 central portion 55 of the strap body may take the form of a piece of metal, preferably sheet metal, to which the flexible strap members 52 and 53 are secured, said members 52 and 53 or any part thereof being made of metal, link mesh, silk or 50 leather cord.

Or the member 55 may be made of leather or other suitable material to which the narrower strips 52 and 53 are stitched or otherwise secured.

In Figs. 6 and 14, I have shown a form of end 55 hook 56, to which the strap ends 31 and 32 may be detachably and adjustably secured. The end hook in this instance takes the form of a buckle, including a pronged swingable member 57 adapted to be forced into engagement with the strap 60 end and thereby to secure it in place, while permitting a range of adjustment.

As shown in Fig. 10, the watch 60 is provided with a single central perforated pin receiving ear 61. Here, the strap ends 31 and 32 are secured 65 to any type of end hook such as 33, 58 or 56, and are preferably, though not necessarily arranged on opposite sides of the ear 61. The bolt or screw 64 is then passed through the cylindrical portions of the end hooks and through the ears, being secured in place in any suitable manner, as by the nut 62, or by screwing the threaded end of the bolt or screw into a correspondingly internally threaded part of the cylindrical portion 63 70 75

of the end hook, in a manner, illustrated for example in connection with Fig. 11.

In Fig. 11, a pair of ears 18 and 19 are provided, each similar to the ear 17. Three strap sections 64, 65 and 66 are there shown, though it will be understood that if desired, the central strap section 65 may be omitted. The nut 62 being eliminated, the end of the screw 61 is screwed into the correspondingly internally threaded cylindrical portion 63 of the lowermost end hook. It will be obvious that my invention may be applied to watches having more than two ears in the same manner.

Referring now to Figs. 12 and 13, I have there shown an end hook structure peculiarly adapted to permit the user to attach the strap to any type of watch ear or pin, such as for example, the fixed pin 21 or the usual removable pin of Fig. 9. In this form of my invention, the end hook comprises the U-shaped buckle frame 70, provided with spaced depending side flanges 171, to which flanges is pivoted a swingable pronged member 72 as at 73. At its other end, the frame 70 terminates in the cylindrical hook member 71 adapted to embrace the watch pin 21 or the like. At its adjacent end, the member 72 is provided with a cylindrical resilient portion 74, which I preferably render more resilient by cutting away a central section such as 75 therefrom so as to space the resilient portions 74 apart, and also to permit the insertion thereinto of a suitable tool to swing the member 72 into open position.

The strap end 76 having been inserted into the frame between the pivot 73 and the flat web of the frame, and the hook 71 having been passed about the watch ear, the member 72 is then rotated in the proper direction to carry the prongs 77 thereof into engagement with the strap end, while at the same time forcing the resilient section 74 past the free edge 78 of the hook 71. The member 72 is thus locked in place due to the tendency of the resilient section 74 to expand against the pin and against said free edge 78. The strap may be readily detached from the pin by inserting the finger nail or a suitable tool in the cut-away part 75 and rotating the member 72 in the proper direction to release the strap. In connection with the fixed pin 21, the spacers, if any are used, should be of hook form, or open 50 along an edge to permit the arrangement thereof on the fixed pin.

It will be understood that the connection just described is adapted for use with the strap sections 31 and 32 as illustrated in Fig. 9, in which case the member 70 is made of the width corresponding to that of the strap end and the tube 36 is used to space the strap ends apart on the pin 16. If desired, however, the portion 71 may be made of greater length than the width of the frame 70 (Fig. 12) in which case the spacers may be dispensed with. Any of the connections specifically described above may be used with a two-part strap body such as shown and described in my co-pending application for patent for Wrist watch strap, Serial No. 557,035, filed August 14th, 1931, or in connection with a strap having only one piece in the width thereof, provided that proper spacers be used on the strap-receiving pin. It will be seen from the above that my invention may take a variety of forms, in all of which, however, the strap end is secured to the watch pin independently of any other strap end and in the proper position on the pin and in relation to any type of watch ear.

75 While I have shown various specific embodi-

ments of my invention, it will be understood that I do not wish to limit myself thereto, but intend to claim my invention as broadly as may be permitted by the state of the prior art and the scope of the appended claims.

I claim:

1. In a wrist watch strap, a non-metallic body portion terminating in a pair of adjacent free end sections, and attaching means including a tubular portion arranged in spaced relation to the strap end and a strap-clamping portion connected to each of said sections, for securing each section to a wrist watch and in predetermined transversely spaced relation to the other section, and means for maintaining said relation comprising at least one tubular member adapted to be arranged interchangeably between said sections or on opposite sides of said sections, or both, said tubular members being of the same inner and outer diameters as those of said tubular portion.

2. In a wrist watch strap for a wrist watch which is provided with pin-receiving members and a pin passing through said members, a non-metallic body member terminating at one end in a pair of free sections, a metallic connection secured to each of said sections, said connection being provided with a strap-receiving and clamping portion adapted to have the extreme end portion of a section partly inserted thereinto, and a tubular pin-receiving portion projecting beyond the clamping portion, and a member tubular throughout its entire length and unmutilated and associated with the connection for positioning said sections relatively to each other on the pin of the watch.

3. In a wrist watch provided with perforated lugs, and a pin removably passed through the lugs, a watch strap having individually movable adjacent end sections, a connection on each of said sections comprising an attaching member securing the connection to the end section and a tubular portion projecting from the attaching member and securing the connection to a pin, and a tubular member arranged coaxially of, on each side of and in edge-abutting relation to the tubular portion of the connection, and adapted to receive the wrist watch pin for spacing the connections relatively to each other on the pin.

4. The combination with the strap-receiving pin of a wrist watch, of a watch strap having a bifurcated end section forming at least two adjacent strap ends, a connection on each of said adjacent ends of the strap, each of said connections having a portion thereof secured to the strap end and having a tubular remaining portion passed about the pin and arranged beyond the strap end, and an unmutilated tubular spacing member arranged coaxially of said tubular portion and at a side of said tubular portion, and in edge-abutting relation to said tubular portion, and on the watch pin.

5. In a wrist watch strap for a wrist watch provided with a strap-holding pin, an end section, means for connecting said section to the pin, a second similar end section adjacent the first-mentioned section, similar means for connecting said second section to the pin, and tubular spacing means associated with the connecting means and mounted on the pin between said sections, for arranging said first and second-mentioned connecting means in predetermined relation.

6. In a wrist watch strap for a wrist watch provided with a strap-holding pin, an end con-

nection comprising a portion clamped about the end of the strap and thereby securing the connection to the strap, an unmutilated tubular portion adapted to receive the pin and integral with the securing portion, and an unmutilated 5 tubular member of substantially the same diameter as that of said tubular portion adapted to be arranged on the pin on at least one side of the tubular portion and beyond said portion to arrange said tubular portion at a desired position 10 on the pin.

7. In a wrist-watch strap for a wrist-watch which is provided with pin-receiving members and a pin passing through said members, a pair 15 of transversely separable adjacent end portions, and means for arranging said end portions in predetermined spaced relation and for securing said end portions to the pin comprising a pair of metallic connections each secured at one part thereof to one of the end portions and at another part thereof being securable to the pin, at least one of said connections being arranged between 20 said members.

8. In a wrist watch strap, an end portion divided transversely into at least two individual end sections, a buckle on each of said sections including a frame terminating in a cylindrical member, a swingable member pivoted to the frame and terminating in a resilient portion 30 bent inwardly through an angle greater than 180° adapted to snap past the edge of the cylindrical member in the operative position of said buckle, a pin passing through the cylindrical members of said end sections, and a tubular spacer adjacent the cylindrical portion of at least one of 35 said buckles.

9. In a wrist watch strap for a wrist watch which is provided with a removable strap-holding pin, a plurality of transversely separable adjacent end portions on the strap, and means for 40 arranging said end portions in predetermined relation and for securing said end portions to the pin, comprising a plurality of separable metallic connections, each of said connections having one part thereof secured to one of the end 45 portions of the strap and having another part thereof of tubular form and adapted to removably receive the pin.

10. In a wrist watch strap for a wrist watch provided with a removable strap-holding pin, an end portion on the strap divided transversely into at least two individual free end sections, a connection on each of said sections, said connection comprising a part secured to the end 50 of the end section, and terminating in a tubular member arranged beyond the extreme end of said end section and adapted to receive the pin, the tubular members of said connections being adjustable transversely relatively to and individually of each other.

11. In a wrist watch strap for a wrist watch which is provided with pin-receiving members and a pin passing through said members, a pair 60 of transversely separable adjacent end portions on the strap, and means for arranging said end portions in predetermined relation on the pin comprising a pair of metallic connections, each of said connections having the inner part thereof secured to one of the end portions of the strap 65 and having an outer part thereof of tubular form

and arranged outwardly beyond the inner part and outwardly beyond and out of contact with the extreme end edge of that end portion of the strap to which said connection is secured by said inner part.

12. In a wrist watch strap, an end portion divided transversely into at least two individual end sections, a buckle on each of said sections including a frame terminating in a completely cylindrical unmutilated member, a swingable 10 member pivoted to the frame and terminating at one end in teeth adapted to engage the end section in the operative position of the buckle to secure the buckle to the end section, a pin passing through the cylindrical members of said 15 buckles, and means for holding said pin, the cylindrical members of said buckles being adjustable on said pin individually of each other and of said means to arrange said cylindrical members in spaced relation to each other or to 20 said means or in edge-abutting relation to each other or to said means.

13. In combination, a wrist watch case, a strap member, a pair of transverse eyes at one of the ends of the strap member, said pair of eyes 25 being relatively movable and supported in spaced apart relation transversely, a detachable pin bar at one end of the case extending through said eyes, and means carried by the pin bar and maintaining said eyes against movement toward 30 each other, said means comprising a third eye arranged in the recess between said pair of eyes and on the pin bar.

14. In combination, a wrist watch having a pair of pin-receiving members, a strap-receiving pin 35 removably held by said members, a watch strap having a bifurcated end part, said end part comprising a pair of transversely movable eyes, said eyes being arranged between said members, and means for arranging said eyes in predetermined 40 spaced relation comprising a third eye arranged between said pair of eyes, said pin passing through all of said eyes and securing said strap and said third eye to the wrist watch.

15. In a wrist watch strap for a wrist watch 45 provided with a strap-holding pin, an end section on the strap, an eye on said section connecting said section to the pin, a second similar end section spaced transversely from the first-mentioned section, a similar eye on said second section 50 connecting said second section to the pin, and tubular spacing means associated with said eyes and mounted on the pin between said sections and between said eyes for arranging and maintaining said eyes in predetermined relation 55 on said pin.

16. The combination with the strap-receiving pin of a wrist watch, of a watch strap having a bifurcated end section forming two strap ends supported in spaced apart relation transversely, 60 an eye on each of said strap ends, each of the eyes having an extension thereof secured to the remainder of the strap, said eyes being passed about the pin and arranged beyond the remainder of the strap, and an unmutilated tubular 65 spacing member arranged on the watch pin coaxially of said eyes and at a side of said eyes and in edge-abutting relation to said eyes.
